UNITED STATES PATENT OFFICE.

ALFRED J. THOMAS, OF BRAINTREE, MASSACHUSETTS.

CUTTING BLOCK FOR DIE PRESSES.

Application filed November 6, 1924. Serial No. 748,077.

To all whom it may concern:

Be it known that I, ALFRED J. THOMAS, a citizen of the United States of America, and a resident of Braintree, in the county of Norfolk and State of Massachusetts, have invented certain new and useful Improvements in Cutting Blocks for Die Presses, of which the following is a specification.

This invention relates to work supporting devices for die presses, and has for its object the production of a removable anvil having attached thereto means for moving a strip of material over the upper face of said anvil in order to secure a new bearing surface for the cutting edge of the die, at each operation of the press.

The invention consists primarily of a metal anvil having secured to its upper face a sheet of fibre board.

The invention further consists in superimposing on this sheet of fibre board, a strip of material such as paper, and providing means for imparting to said strip, a step by step motion during the operation of the press.

The invention further consists of certain novel features of construction and arrangement of parts which will be understood readily by reference to the description of the drawings and to the claims to be herein-after given.

For the purpose of illustrating the invention, one preferred form thereof is illustrated in the drawings, this form having been found to give satisfactory and reliable results although it is to be understood that the various instrumentalities of which the invention consists can be variously arranged and organized and the invention is not limited to the precise arrangement and organization of these instrumentalities as herein shown and described except as required by the scope of the appended claims.

Of the drawings:

Figure 1 represents a vertical section of an anvil or work supporting member embodying the principles of the present invention, said anvil being shown supported upon the bed of a die press and beneath the reciprocating pressure plate thereof.

Figure 2 represents a plan of said anvil, and

Figure 3 represents a section of the anvil on line 3, 3, on Fig. 1, said figure being drawn to a reduced scale.

Similar characters indicate like parts throughout the several figures of the drawings.

In the drawings 10 is the bed of a die press and 11 the vertically reciprocating pressure member thereof. As the die press forms no part of the present invention and any well known press may be used in connection with the invention, it is deemed unnecessary to further illustrate said press.

Upon the bed 10 is mounted a metal anvil 12 which is not attached to said bed, but retains the position in which it may be placed on account of the weight of said anvil.

The anvil 12 has a deep depression 13 in its front end and also depressions 14 in the sides thereof as indicated in Fig. 3.

These depressions 13, 14 are provided so that a shoe upper may be placed upon the front portion of the anvil with portions thereof positioned in said depressions, so that the portion to be operated upon may be made to lie flat beneath the die 15 which is used to cut designs in said upper.

If a block was used with vertical sides it would be impossible to position the upper so that any portion thereof would be flat upon the anvil.

In order to protect the cutting edges of the die 15 when the dieing out operation is being performed, the anvil 12 is provided with a fibre board plate 16 which is secured to said anvil by means of the centrally disposed screw 17 about the axis of which the plate 16 may be rotated, so that when the forward part of the plate becomes unserviceable the rear part thereof may be moved into position over the front part of the anvil 12.

When both ends of the plate 16 have become unserviceable the plate may be removed and a new plate substituted therefor.

The anvil has forwardly extending ears 18 in which is revolvably mounted a roll 19 having a strip of paper 20 wound thereon.

The paper strip 20 passes partially around guide rolls 21, and over the upper face of the plate 16 to the rear of the anvil 12 where it passes between the feed rolls 22,

23 to a receiving roll 24 on which it is wound as said strip is fed thereto.

The feed roll 23 has a ratchet 25 rotatable therewith with which a pawl 26 coacts to give a step by step motion to said feed roll 23.

An endless belt 27 from the roll 23 to the receiving roll 24 causes these rolls to rotate in unison.

10 The roll 22 is provided with means for adjusting it toward and from its companion roll 23, thereby regulating the gripping contact of the rolls 22, 23 with the strip 20.

15 The pawl 26 is pivotally mounted on a plunger 28 adapted to reciprocate vertically in the chamber 29 of a cylindrical member 30 mounted on the rear end of the anvil 12.

Beneath the plunger 28 is a helical spring 31 tending to force the plunger 28 upwardly so that the stem 32 thereof will extent a short distance above the top of the die 15 so that when the pressure member 11 descends it will strike said stem 32 and force the plunger 28 downwardly against the tension of the spring 31, thereby permitting the pawl 26 to engage a new tooth of the ratchet 25.

As soon as the die 15 is removed from the work W, after the pressure member 11 has moved upwardly, the spring 31 will force the plunger 28 upwardly, causing the pawl 26 to impart a partial rotation to the ratchet 25, and thus feed the strip 20 and wind it upon the roll 24.

35 A collar 33 surrounds the stem 32 and is threaded to the upper end of the cylindrical member 30, the lower end of this collar coacting with a shoulder 34 on the plunger 28 to limit the upward movement thereof.

40 A member 35 threaded to the lower end of the cylindrical member 30 is adapted to regulate the tension of the spring 31.

The paper strip 20 is of sufficient thickness to receive the cutting edges of the die 15 without being cut through, but in case these cutting edges do pass through the paper strip they will not be injured as they will simply cut into the face of the fibre board plate 16.

50 It is desirable to always have a flat plane face for the cutting edges of the die to coact with when the work W is being operated upon and by giving the strip 20 a step by step movement at each cutting operation a new surface is provided for each successive operation.

This is of considerable importance as by this means a cleaner cut is assured.

60 It is believed that the operation and many advantages of the invention will be apparent without further description.

Having thus described my invention, I claim:

65 1. In a die cutting block, the combination of a weighted metal anvil freely movable on

the bed of a die press; a strip of flexible material superimposed thereon; and means supported by said anvil for moving said strip over the surface thereof.

2. In a die cutting block, the combination 70 of an anvil freely movable on the bed of a die press; two rolls mounted in bearings at the ends of said anvil; a strip of paper on one roll extending over the upper face of said anvil and adapted to be wound on the other roll; and means actuated by the pressure member of said press for rotating said receiving roll.

3. In a die cutting block, the combination 80 of an anvil freely movable on the bed of a die press; two rolls mounted in bearings at the ends of said anvil; a strip of paper on one roll extending over the upper face of said anvil and adapted to be wound on the other roll; and means actuated by the pressure member of said press for rotating said receiving roll and feeding the strip thereto.

4. In a die cutting block, the combination 90 of an anvil freely movable on the bed of a die press, two rolls mounted in bearings at the ends of said anvil; a strip of paper on one roll extending over the upper face of said anvil and adapted to be wound on the other roll; rolls at the rear of the anvil for feeding said strip; and means actuated by the pressure member of said press for rotating said receiving roll and feeding

rolls. 95

5. In a die cutting block, the combination 100 of an anvil freely movable on the bed of a die press; two rolls mounted in bearings at the ends of said anvil; a strip of paper on one roll extending over the upper face of said anvil and adapted to be wound on the other roll; rolls for feeding said strip; a ratchet revoluble with one of said feed rolls; and a reciprocating pawl coacting with said ratchet and adapted to be actuated by the downward movement of the pressure member of said press. 105

6. In a die cutting block, the combination 110 of an anvil freely movable on the bed of a die press, two rolls mounted in bearings at the ends of said anvil; a strip of paper on one roll extending over the upper face of said anvil and adapted to be wound on the other roll; rolls for feeding said strip; a ratchet revoluble with one of said feed rolls; a reciprocating pawl coacting with said ratchet and adapted to be actuated by the downward movement of the pressure member of said press; and a spring pressed plunger carrying said pawl. 115

7. In a die cutting block, the combination 120 of an anvil freely movable on the bed of a die press; two rolls mounted in bearings at the ends of said anvil; a strip of paper on one roll extending over the upper face of said anvil and adapted to be wound on the other roll; rolls for feeding said strip; 125

a ratchet revoluble with one of said feed rolls; a reciprocating pawl coacting with said ratchet and adapted to be actuated by the downward movement of the pressure member of said press; a spring pressed plunger carrying said pawl; and means for controlling the movement of said plunger.

Signed by me at 746 Old South Bldg., Boston, Mass., this 3rd day of October, 1924.

ALFRED J. THOMAS.
